UNITED STATES PATENT OFFICE.

OTTO RIEKE, OF CHICAGO, ILLINOIS.

SPRING-WINDING MECHANISM.

1,193,300.

Specification of Letters Patent. Patented Aug. 1, 1916.

Application filed March 29, 1915. Serial No. 17,739.

To all whom it may concern:

Be it known that I, OTTO RIEKE, a citizen of the United States, residing at Chicago, in the county of Cook and State of Illinois, 5 have invented certain new and useful Improvements in Spring-Winding Mechanism, of which the following is a specification.

The winding mechanism which is the subject-matter of the present application for 10 patent is designed more particularly for winding the spring motor of talking machines, a reciprocatory lever being employed in the place of the usual crank handle.

The invention has for its object to provide 15 a winding mechanism of the kind stated embodying certain novel and improved features of construction and arrangement of parts to be hereinafter described and claimed, reference being had to the accompanying drawing in which—

Figure 1 is an elevation of a fragment of a talking machine to which the invention is applied, and Fig. 2 is a plan view of the winding mechanism.

Referring specifically to the drawing, 5 25 denotes the box of a talking machine in which is housed the spring motor 6 which drives the turntable 7 supporting the record disk. The spring of the motor has a winding shaft 8 provided with a suitable pawl-and-ratchet mechanism 9 to prevent the shaft from slipping back. The outer end of the shaft carries two clutch members 10 and 11, respectively, the same being disks 30 35 having their contiguous faces toothed to intermesh, the teeth being arranged to transmit motion in one direction and to slip in the opposite direction. The disk 10 is fast on the shaft, and the disk 11 is loose 40 and slideable thereon. Integral with the disk 11, or separate and made fast thereto, is a bevel pinion 12. A spring 13 holds the disks in mesh and yields to allow the same to separate. The spring is coiled around 45 the shaft between the bevel pinion and a bearing 14 supporting the outer end of the shaft.

In mesh with the bevel pinion 12 is a curved rack bar 15 connected at one end to a hand lever 16 which is fulcrumed at its 50 inner end, as indicated at 17, to a suitable support in the box 5. The lever and the rack bar swing in a horizontal plane. The free end of the lever extends out of the box through a side slot 18, and is shaped into a 55 handle 19.

It will be evident from the foregoing that when the lever 16 is swung back and forth, the rack bar 15 rotates the pinion 12 alternately in opposite directions, and when 60 turning in one direction the clutch disk 11 of said pinion is locked to the clutch disk 10 and thus imparts a rotary movement to the shaft 8 in the same direction. When the pinion turns in the opposite direction, no 65 motion is transmitted to the shaft as the pinion slips back and the disk 11 does not take hold of the disk 10, the pawl-and-ratchet mechanism 9 holding the shaft 70 against slipping back.

I claim:

The combination with a spring motor; of a rotary shaft for winding the motor spring, coöperating clutch members on the shaft, one of said members being fast on the shaft 75 and the other member being loose and slideable on the shaft, a pinion fast on the last-mentioned clutch member, yielding means for holding the clutch members locked together, a rack bar in mesh with the pinion, 80 and a lever extending in the direction of the shaft and connected to the rack bar, said rack bar extending from one side of the lever, and the latter being mounted to swing toward and from the shaft. 85

In testimony whereof I affix my signature in presence of two witnesses.

OTTO RIEKE.

Witnesses:

S. J. LEHRER,
H. G. BATCHELOR.
